UNITED STATES PATENT OFFICE

HARRY L. COMPTON, OF WASHINGTON, DISTRICT OF COLUMBIA, ASSIGNOR TO
AMERICAN DAIRY SUPPLY CO., A CORPORATION OF MAINE

COVER-ALL BOTTLE CAP

Application filed July 23, 1929. Serial No. 380,325.

This invention relates to cover-all cap closures for bottles or jars, and is more especially intended to cover and protect from deposited dust the tops of milk bottles delivered for the uses of householders and which are ordinarily exposed. This invention belongs directly to that type of closure or hood which extends externally over the top of the bottle and downwardly for a short distance all around by which the entire top portion of the bottle is enclosed.

It is an object of this invention to provide a closure of the nature stated which may be easily and cheaply manufactured in the forms described, and is of a particularly durable nature.

An object of this invention further is to produce a hood or cap which may be applied in one form by a suitable capping machine, and which when made in another form may be placed upon the bottle by hand.

Another object is the construction of a milk bottle cap which in either of the forms herein set forth may be replaced by hand after the first removal from the bottle however originally applied thereto, in order that any milk remaining in the bottle may be completely protected for future use.

The foregoing and other kindred objects of this invention are attained in a very useful and serviceable degree by constructing the closure substantially in accordance with the accompanying drawings forming a part of this specification.

35 Of the drawings, Fig. 1 represents in section the upper portion of a milk bottle having this invention, shown also in section, applied thereto.

40 Fig. 2 is a sectional view of the upper portion of a milk bottle having applied thereto a modified form of this invention shown also in section.

45 Fig. 3 is a side view of one of the clips or clasps before being secured to the cap.

Fig. 4 is an outside view of one of the clips detached.

50 Fig. 5 is a sectional view of a cap fashioned in accordance with this invention and somewhat enlarged, setting forth a modi-

fication of the clip or clasp member herein described.

Fig. 6 is a sectional view of part of the cap shown in Fig. 5 to illustrate the transverse bending of the clip. The section is taken on the broken line 6—6 of Fig. 5.

Throughout the drawings and description the same number is used to refer to the same part.

Considering the drawings, Fig. 1, a bottle 1 has thereon a cap 2 which is of the ordinary pattern formed with a crimped or folded downwardly extending portion or skirt enclosing the top portion of the bottle. At any number of separated points clips or clasp members 3 are located, and the clips extend vertically inside and outside the skirt or wall of the cap and pass under the lower edge thereof as illustrated. There may be any number of clips 3, of any width, regularly or irregularly spaced apart, and in Fig. 1 the clips are shown as made of bendable non-resilient metal, in order that they may be bent either by hand, by tool or machine inwardly against the exterior of the rounded throat 5 of the bottle.

In Fig. 2 is shown a molded cap 6, the skirt or depending wall of which may be without crimps or folds. Spaced around the cap 6 are clips 7 in this modification. The clips are of resilient metal, and the cap is molded in such form and the clips are so shaped in correspondence therewith that the cap may be pressed downwardly by hand upon the rounded top 8 of the bottle 9. The cap may be conveniently removed by hand, but while it is in position upon the bottle top it tightly closes the mouth of the bottle and protects the entire top.

This invention is not intended to be limited to the precise sizes and forms of the clips as illustrated in Figs. 3 and 4.

In both Figs. 1 and 2 there will be noted small pointed tangs 4 which are stamped from the flat metal clip and penetrate the material of the cap when clamped thereon. The clips are thus additionally secured to the depending wall of the cap. It is not intended to limit this invention to the tangs as set forth, as other means may be ob-

viously substituted. It will be understood further that the size or material of the cap, the size, material or disposition of the clips or the particular shape thereof are not to be regarded as limitations of this invention, as changes of these features are readily made.

In the modification set out in the enlarged Figs. 5 and 6, the cap 10 is composed of layers of paper or like one upon another, and the outer surface of the clip 12 is covered with an adherent uninterrupted coating 11 of fabric or plastic which is unaffected by moisture. No milk can come directly into contact with metal. The application of the clips to the caps is the same as in the forms of the invention previously described.

In operation, either of the forms may be applied to the bottle by a capping machine, and when once in position the cap will resist ordinary displacing blows or contacts met with in the usual handling and delivery of bottles of milk.

If so desired the clips may be sufficiently stiff to require a tool for the removal of the cap, but that is not essential. When once removed the cap may be pressed down into position to protect any remaining contents of the bottle.

It will be noted particularly in Fig. 6 that when the cap is applied to the top of a bottle by pressure, the clip is bent in a vertical curve around the exterior of the neck of the bottle, and the clip also receives a further and transverse bend thus adding to the security of the cap fastening. When the clips are made relatively wide the transverse bend therein is more extended.

Having now explained this invention as to its construction and operation, I claim:—

1. A cover-all cap, comprising a cap extending over the top of a bottle or jar and downwardly, spaced clips vertically disposed, the said clips having portions arranged on the inside and outside of the downwardly extending wall of the cap and passing under the lower edge thereof, and means borne by the clips and penetrating the wall of the cap to additionally secure the clips to the cap.

2. A cover-all cap, comprising a cap extending over the top of a bottle or jar and downwardly, said cap being composed of non-metallic material and compressible, spaced clips of bendable metal, the said clips having portions arranged on the inside and outside of the downwardly extending wall of the cap and passing under the lower edge thereof, whereby the said cap may be compressed to conform to the external shape of the top of a bottle or jar and said clips may be bent into like conformity and pressed into the material of the cap.

3. A cover-all cap, comprising a cap ex-

tending over the top of a bottle or jar and downwardly, said cap being composed of non-metallic material and compressible, spaced clips of bendable metal, the said clips having portions arranged on the inside and outside of the downwardly extending wall of the cap and passing under the lower edge thereof, the said clips being coated with an uninterrupted external adherent skin of moisture resisting substance, whereby the said cap may be compressed to conform to the external shape of the top of a bottle or jar and said clips may be bent into like conformity and pressed into the material of the cap.

4. A cover-all cap, comprising a cap extending over the top of a bottle or jar and downwardly, spaced clips vertically disposed, the said clips having portions arranged on the inside and outside of the downwardly extending wall of the cap and passing under the lower edge thereof, and the said clips being bent in a vertical curve and a transverse curve when applied externally to the neck of a bottle.

In testimony whereof I affix my signature.

HARRY L. COMPTON.
